INFERIEURE), FRANCE.

TRAWLING GEAR.

Application filed December 6, 1923. Serial No. 678,905.

To all whom it may concern:

Be it known that we, RENÉ LOUIS MARIE DANIELOU and JACQUES JULES VERHOEVEN, citizens of the French Republic, residing at 5 Lorient, Morbihan, in the French Republic, have invented new and useful Improvements in Trawling Gears, of which the following is a specification.

This invention relates to the trawling 10 gears used in connection with the fishing nets which are adapted to be towed by a single boat through the intermediary of two cables or hawsers connecting to the boat two boards situated during the fishing at 15 a great distance from one another, these boards being connected on the other hand with the braces of the wings of the net by two cables or lines of great length which converge towards the latter.

20 With devices of this class, such as are constructed up to the present, the immersing of the net in the water and its removal, offer certain difficulties and drawbacks which are obviated by the arrangement 25 which is the object of the present invention.

According to the invention, for each board, the tow hawser is removably attached to one face of said board and the line leading to the brace of the net wing is 30 removably attached to the other face of the board, these attaching points of the hawser and the line being connected by means of an intermediary cable.

In the appended drawing, given by way 35 of example:

Fig. 1 is an elevation of the board provided with its attaching means.

Fig. 2 is a plan view of the whole device in operation and when towed.

40 Fig. 3 is a view of the successive cables, after the removal of the board, during the winding of said cables on the fishing winch.

Fig. 4 shows a modification of the means for connecting the intermediary cable and 45 the board to the line.

As is well known, the hawser 1 connected with the boat is attached at the other end to the board 2 as well as the line 3 which proceeds to the brace of the net wing. In 50 the construction shown in the drawing, the board 2 is provided on its inner face with two brackets 4 carrying a chain 5 provided with a shackle 7. Between the brackets, the board is provided with an opening 8. To

the outer face of the board is attached a 55 crow's foot 9 carrying a shackle 10.

The hawser 1 carries at its end, towards the board, a turnbuckle 11 and a link 12 which can be engaged in the shackle 7. The line 3, leading to the net, is provided at its 60 end with a turnbuckle 15 and a link 13 which can be engaged in the shackle 10. A connecting cable 14 extends through the opening 8 of the board and connects together the two links 12 and 13. The length 65 of said connecting cable is greater than the distance $x-y$ between the shackles 7 and 10, during the operation, when the net is towed.

When the trawling net is at the bottom 70 of the water, in order to draw it, that is to say to bring it on board, each hawser 1 is wound upon the fishing winch, and when the corresponding board is brought out of the water, it is hung upon the bracket adapted 75 to receive it, the winch is rotated backward so as to slacken the hawser 1, and the link 12 can easily be removed from the shackle 7. The winch is then rotated forward, in order to wind the hawser 1 and 80 then the cable 14, the shackle 10 thus passing through the hole 8 in the board. The crow's foot 9 is thus slackened, so that one can readily remove the link 13 from the shackle 10. One can then wind the line 3 on 85 the winch, so as to draw in the net. The line 3 is connected, as is known, with the brace of the net wing by a crow's foot, and to the latter is often attached one or more cables proceeding to the top rope and to the 90 ground rope of the net. The ends of the crow's foot and the ends of these cables will finally pass through the opening 8 in the board when the net is brought on deck, and one can thus readily detach them from the 95 line 3 so as to finally hoist the net on board.

To immerse the net and the boards into the water, the inverse operation is performed.

Other means may be used for connecting 100 the intermediary cable 14 to the line 3, while affording the same advantages, i. e. while permitting to wind the line 3 by passing the same through the opening 8 of the board.

The construction shown in Fig. 4 is particularly adapted for the case in which the cheeks of the drum of the winch will not

allow the passage of the members 11, 12 and 15 constructed as shown in Figs. 1 and 2. In this case the cable 14 and the line 3 are connected by means of two couplings or splices 25 so arranged that one of the cables is slackened and allows the rapid insertion or removal of a shackle 24 removably attached to the crow's foot 9.

It will be seen that by means of this arrangement, one can wind the lines 3 as well as the hawsers 1 on the fishing winch instead of having to mount the lines by hand, which latter operation was very difficult, especially in bad weather. The lines can also be manipulated without being obliged to provide on board any additional installations. On the other hand the lines, being no longer manipulated by hand, can have any desired makeup and are no more necessarily made of mixed rope, and all risk of wounds occasioned by steel pieces projecting out of the hemp are obviated.

Lastly, the operation is very rapid, both for the drawing and for the laying; it suffices in fact, for drawing in the net, to hang up the two boards and to remove the shackles 7 and 10. The operation of laying is also easier than before, for the risk of engaging the lines or boards in the propeller is thus considerably reduced, and moreover, the vessel preserves its freedom of movement during the laying operation which is not possible when this is done by hand.

Finally, the opening in the board has the advantage of diminishing the resistance of the water.

It will be understood that the intermediary cables may not be immersed together with the net and boards, but can be temporarily attached to the tow hawsers on deck as the gear comes aboard, previous to the detaching of each board at its two points of attachment so that when the board is detached haulage can proceed on one and the same winch.

The intermediary cable can also form an integral part of the tow hawser or of the line, or of both at a time, the shackles 7 being then connected in a suitable manner with the cable.

The invention is not limited, of course, to the details of construction shown and described, and these have been chosen only by way of example.

Having now described our invention what we claim as new and desire to secure by Letters Patent is:

1. A towing device for trawl nets comprising a towing line adapted to be connected to one of the net wings, an otter board, a tow hawser adapted to be connected to the boat, means for detachably connecting the tow hawser to the inner face of said board, means for detachably connecting the towing line to the outer face of said board and an intermediate cable adapted to connect said hawser to said towing line.

2. A towing device for trawl nets comprising a towing line adapted to be connected to one of the net wings, an otter board, brackets on the inner face of the board, a tow hawser adapted to be connected to the boat, a detachable shackle for detachably connecting the tow hawser to said brackets, means for detachably connecting the towing line to the outer face of said board and an intermediate cable adapted to connect said hawser to said towing line.

3. A towing device for trawl nets comprising a towing line adapted to be connected to one of the net wings, an otter board, brackets secured on the inner face of said board, a crow foot member secured to the outer face of said board, a tow hawser adapted to be connected to the boat, a shackle for detachably connecting the tow hawser to said brackets, a shackle for detachably connecting the towing line to the crow foot member and an intermediate cable adapted to connect said hawser to said towing line.

4. A towing device for trawl nets comprising a towing line adapted to be connected to one of the net wings, an otter board, brackets secured on the inner face of the board, a crow foot member secured on the outer face of said board, a tow hawser adapted to be connected to the boat, means for detachably connecting the tow hawser with the said brackets, a loop formed at the end of the towing line, a detachable shackle adapted to engage into said loop for connecting the towing line to the crow foot member and an intermediate cable adapted to connect said loop to the tow hawser.

In testimony whereof we have signed our names to this specification.

RENE LOUIS MARIE DANIELOU.
JACQUES JULES VERHOEVEN.
